UNITED STATES PATENT OFFICE.

WILLIAM J. BRADLEY, OF TROY, AND JOHN MATHISEN, OF LANSINGBURG,
NEW YORK.

DESIGN FOR A HORSESHOE.

SPECIFICATION forming part of Design No. 29,712, dated November 22, 1898.

Application filed September 8, 1898. Serial No. 690,541. Term of patent 14 years.

To all whom it may concern:

Be it known that we, WILLIAM J. BRADLEY, of the city of Troy, and JOHN MATHISEN, of the village of Lansingburg, county of Rensselaer, State of New York, have invented and produced a new and original Design for Horseshoes, of which the following is a specification, reference being had to the accompanying drawings, forming a part thereof, in which—

Figure 1 is a perspective of a horseshoe, illustrating our design; and Fig. 2 is a section taken on the line $x-x$ of Fig. 1.

As illustrated in the accompanying drawings, the leading features of our design consist in the form of the hoof-face II, the tread-face T, and the form given to the outer and inner edges of the shoe. The hoof-face II is flat. The tread-face T has the rim R, formed with the outwardly projected and rounded edge r^2 , connecting with the outer edge E' of the shoe, and this tread-face between the rounded edge r^2 of the rim R and the in-

ner edge E^2 is projected inwardly and downwardly in ogee curvature, as indicated at O. 25 The outer edge E' of the shoe, as indicated at E', is slightly curved outwardly. The heel ends h^2 of the shoe are rounded off at h^3 , with a beveled edge projecting outwardly and extended upwardly from the tread-face T to 30 the hoof-face II.

Having thus described our design, what we claim, and desire to secure by Letters Patent, is—

The design for a horseshoe as herein shown 35 and described.

Signed at the city of Troy, New York, this 14th day of June, 1898, and in the presence of the two witnesses whose names are hereto written.

WILLIAM J. BRADLEY.
JOHN MATHISEN.
